tion of New York

Application March 21, 1931, Serial No. 524,329

25 Claims. (Cl. 29—103)

The present invention relates to gears which mesh with axes angularly disposed and non-intersecting and particularly to what is known as hypoid gears or gears whose axes are angularly disposed and offset and in which one member of the pair has teeth on its side face.

With the methods heretofore used for producing such gears, there have been definite practical limitations as to the amount of offset obtainable in the pair. Meantime, however, in the automotive field especially, there has been a growing demand for larger offsets in order to permit further lowering of the car bodies.

The present invention has for its primary purpose to provide hypoid gearing in which larger offsets can be obtained even in the ratios commonly used in the automotive field.

Among other objects, the invention has for its purpose to provide hypoid gearing each of whose members can be manufactured in a simple operation and inexpensively, and in which one member of the pair can be hobbed.

The invention broadly has a three-fold character. It consists first in a new form of gearing which comprises a novel form of worm meshing in offset relation with a novel form of gear; second, in a novel form of hob employed to produce the gear; and third, in the new method whereby the gear is hobbed. The present application relates specifically to the hobbing process and to the hob employed therein.

The principal objects of the invention have been described. Other objects of the invention will appear hereinafter from the specification and from the recital of the appended claims.

In the drawings:

Figure 1 is a side elevation of a pair of gears produced according to this invention;

Figures 2 and 3 are a plan view and a side elevation, respectively, illustrating the preferred method of hobbing the gear or larger member of the pair; and

Figure 4 is a sectional view which may be considered a section in an axial plane through either a taper worm or a taper hob constructed according to this invention.

It has heretofore been suggested (see the Trbojevich Patent No. 1,647,157 of November 1, 1927) that hypoid gearing might be produced by using a worm as the pinion or driver and by cutting the gear with a hob which is a counterpart of the worm and which during cutting is positioned and maintained in the same offset and angular relation to the gear blank as the worm itself occupies when in mesh with the finished

gear. This method has the advantage of simplicity because the worm can be produced in an ordinary lathe and the gear can be hobbed without a generating roll, but such hypoid gearing up to the present has not come into use commercially. 5 The principal disadvantage has been that it has heretofore been confined to use in large reductions for, up to the present, it has not been practical to make pairs employing other than a single-thread worm.

My invention constitutes an improvement on the type of gearing described in the Trbojevich patent above mentioned in that it permits of using a multiple-thread worm as one member of the hypoid pair, the number of threads in the worm 15 being determined by the ratio desired. The method of cutting the gear is of the same general character described in the Trbojevich patent, the gear being cut with a hob, which is a counterpart of the worm or generally so, by rotating the hob 20 and gear blank together in timed relation and imparting a simple depthwise feed motion to cut teeth of proper depth on the gear blank, but the worm and hob and, therefore, the gear are different in construction from the worm, hob and 25 gear illustrated in the Trbojevich patent.

Heretofore, when a multiple-thread taper worm or hob has been used to cut a tapered gear, the teeth cut in the gear have had pressure angles changing from their outer to their inner ends to 30 so extreme a degree as to render the gear impractical for use. In my improved gearing, however, instead of using a worm of uniform pressure angle from one end to the other, as is the usual practise and as is described in the Trbojevich patent, 35 I modify the pressure angles of the threads of the worm and of the corresponding hob from one end to the other and to such an extent that a practical form of gear tooth is obtained, a tooth either of uniform pressure angle from end to end or one 40 varying in pressure angle within narrow and unobjectionable limits.

As the pressure angles of teeth of a tapered gear cut with a multiple-thread hob of uniform pressure angle are excessive at the outer or large 45 ends of the teeth and too small at the inner or small ends of the teeth, I make the threads of my hob and worm so that the pressure angle is greatest at the small end of the hob, the end which cuts the inner ends of the teeth of the 50 gear, and least at the large end of the hob, the end which cuts the outer ends of the teeth of the gear. Incidentally this structure gives added strength to worm and hob for the increased pressure angle of the threads at the small end of the 55

hob and worm give increased strength where it is most needed. As it is desirable to cut both bevel and hypoid gears with teeth tapering in depth from their outer to their inner ends, the 5 teeth of my hob and the threads of my worm are tapered in height from the large to the small end of the hob and worm. Now with this construction, if the hob thread were of the same lead on opposite sides, the teeth at the small 10 end would be of disproportionate width at their tips or lands and would accordingly cut the inner ends of the tooth spaces of the gear disproportionately wide. To avoid this condition, I have found it desirable to form the threads of 15 both hob and worm of different lead on opposite sides. For the sake of simplicity in manufacture and the greater ease in calculating gears and hob, both sides of the threads are, however, made of uniform lead. If gears having teeth of 20 parallel depth, that is, of uniform height from end to end, were to be cut, the threads of hob and worm would not have to be tapered in height and the tips or lands of the threads could be made of uniform width from end to end of hob 25 and worm by changing the pressure angle alone.

Referring to the drawings by numerals of reference, 10 denotes the gear and 11 the worm or pinion of a pair of hypoid gears constructed according to the present invention. The axis 12 of the worm is offset from the axis 13 of the gear a distance X . The worm is tapered and is provided with a plurality of threads or teeth 14 which are curved longitudinally about the axis of the worm and which mesh with the correspondingly curved teeth 15 of the gear. The teeth of the gear are cut conjugate to the threads of the worm. The number of teeth in worm and gear are determined by the reduction desired.

40 Figure 4 shows in axial section, the preferred construction of the worm. It has threads 14 whose sides 16 and 17 are of changing pressure angle from end to end. Thus, the pressure angle of the sides 17 of the threads 14 increases 45 from right to left, the pressure angle at a being larger than at $a1$ which in turn is larger than at $a2$ and so on, the pressure angle for the sides 17, in the section shown, being at a minimum at $a4$ and at a maximum at a . Likewise, on the other side 16 of the thread, the pressure angles 50 vary from b to $b4$, being at a maximum in the section shown, at b and a minimum at $b4$. The change in pressure angle from end to end on the two sides of the worm threads is such as to 55 permit of making the teeth 15 of the gear of approximately uniform pressure angle from end to end. It will be noted that the pressure angles of opposite sides of the worm thread are largest at the small end of the worm. This 60 gives added strength where it is most needed.

The worm is preferably made with teeth tapering in height from its large end to its small end as shown and the gear has teeth tapering correspondingly in height from their outer to 65 their inner ends.

70 For the purpose of simplicity in manufacture both of the worm and of the corresponding hob for cutting the gear, and also because of the desirable tooth shapes obtainable on the gear, the threads of the worm are turned so that their sides 16 and 17 are straight in axial section as shown. Likewise, because of the manifest advantages in manufacture and the greater ease in calculating the gears, I prefer to make the 75 sides of the worm threads of uniform pitch in

axial section, but to avoid excessive width of the threads at their small ends with a corresponding excessive width of the tooth spaces of the gear 15 at their small ends, which would result if the threads of the worm were tapered in height without any other change, the threads of the worm are made of different pitch on opposite sides. 5

20 denotes the pitch surface of the worm when running in mesh with its mate gear 10. 10 21 denotes the top surface of the worm and 22 its root surface. 24 denotes a line parallel to the root surface of the worm. For convenience in manufacture, as will hereinafter appear, I prefer to make the sides 16 and 17 of the threads 15 of the worm of uniform pitch along this line. The pitch of the sides 16 of the thread 14 is indicated at P . The pitch of the sides 17 of the threads is indicated at P' . The two pitches P and P' are each uniform along the line 24, but 20 they are different.

The gear will have teeth 15 whose sides are correspondingly of uniform pitch along a line coinciding with the projection of the worm axis, the pitch being different on the two sides of the 25 teeth corresponding to the difference in pitch of opposite sides of the worm threads.

The gear 10 of the pair is cut with a hob H which is preferably made a counterpart of the worm 11. It is formed with a plurality of threads 30 which are gashed at 25 and relieved to form cutting teeth 26. If an exact counterpart of the worm, the number of threads in the hob will be the same as the number of threads in the worm 11 and like the threads 14 of the worm 11, the 35 pressure angle of the sides of the thread of the hob will change from one end of the hob to the other and in the same respect and to the same extent as the pressure angle of the threads of the worm. The leads of the hob threads will be 40 different on opposite sides of the thread, the pitches of opposite sides of the hob threads will be different and equal, respectively, to the pitches p and p' of opposite sides of the worm threads. The pitches of the sides of the hob threads will 45 be uniform along a line corresponding to the line 24 and parallel to the root line 22 of the hob. This construction permits of readily relieving the hob on a lathe such as described in my pending application No. 447,011 of April 24, 1930. The 50 teeth of the hob will taper in height from the large end to the small end thereof and preferably to the same extent as to the teeth of the worm. As stated with reference to the worm, the increased pressure angle of the teeth at the small 55 end of the hob gives increased strength. The sides of the hob will be straight in axial section as shown in Figure 4. This permits of relieving the hob with a straight-sided lathe tool placed on center and gives a more desirable tooth structure in the gear and in the corresponding worm. Figure 4 may be considered an axial section either through the worm 11 or the hob H.

The worm can be cut upon a machine similar to that described in my pending application No. 65 447,011 by omitting the relieving attachment and simply using the machine as a worm-cutting lathe.

The gear 10 is cut by positioning the hob H with its axis 28 offset from the axis 13 of the 70 gear blank the same distance X as the worm 11 is offset when in mesh with the gear and the hob is preferably positioned, also, with reference to the gear blank so that its axis 28 is inclined to the axis 13 of the gear blank at the same angle 75

as that to which the worm 11 is inclined to the axis 13 of the gear 10 when the two are in mesh. In the drawings, this angle is 90°. The offset between the cone apex 29 of the hob H and the cone apex 30 of the gear blank 10 is preferably the same as the offset between the cone apex of the worm and the cone apex 30 of the gear when the worm and gear are in mesh. If the apex of the worm when in mesh with the gear lies on the line X perpendicular to the axes 13 and 12, respectively, of the gear and worm, the offset is, of course, zero. The pitch cone angle 31 of the hob is preferably the same as the pitch cone angle of the worm 11.

15 To cut the gear, the hob H is positioned as described, and the hob and gear blanks are rotated continuously on their axes 28 and 13, respectively, in timed relation while a depthwise feed is produced between the hob and blank to cause teeth of proper depth to be cut in the blank. During this feed motion, the angular and offset relations of the hob and blank axes are maintained constant so that when the hob has reached full depth position, its teeth will sweep out the 20 whole of the finished tooth surfaces of the gear 10. There is no generating roll employed. The gear may be cut upon a machine of the type described in the Trbojevich patent above mentioned.

25 30 I have stated above that preferably the hob is made a counterpart of the worm 11. However, the dimensions of the hob or its position in cutting the gear may be slightly different from the dimension of the worm or the position of the worm when it meshes with the gear, for the purpose of obtaining a localization of tooth bearing between the worm and gear, as will be readily understood by those skilled in the art.

While the invention has been described in connection with the production of a pair comprising a tapered gear and worm, it will be understood that the principles of the invention apply broadly, also, to such hypoid pairs as include a cylindrical worm and a conjugate mating crown gear. In general it may be said that while I have described particular embodiments of my invention, it will be understood that the invention is capable of various further modifications and uses and that this application is intended to cover any adaptations, uses, or embodiments of the invention following, in general, the principles of the invention and including such departures from the present disclosure as come within known or customary practice in the gear art and as may be applied to the essential features hereinbefore set forth and as fall within the scope of the invention or the limits of the appended claims.

Having thus described my invention, what I claim is:

60 1. A hob formed by gashing and relieving a thread to form a series of finishing teeth which together generate the final finished shape of the work, said thread being of different lead on opposite sides but of uniform lead on each side and being of straight profile in an axial plane.

65 70 2. A taper hob formed by gashing and relieving a thread to form a series of finishing teeth which together generate the final finished shape of the work, said thread being of different lead on opposite sides but of uniform lead on each side and being of straight profile in an axial plane.

75 3. A taper hob formed by gashing and relieving a thread to form a series of finishing teeth which together generate the final finished shape of the work, said thread along a line parallel to its root

line being of different lead on opposite sides but of uniform lead on each.

4. A taper hob formed by gashing and relieving a thread to form a series of finishing teeth which together generate the final finished shape of the work, said thread on each side being of changing pressure angle from one end to the other and of different lead on its opposite sides.

5. A taper hob formed by gashing and relieving a thread to form a series of finishing teeth which together generate the final finished shape of the work, said thread on each side being of changing pressure angle from one end to the other and being of different lead on its opposite sides but of uniform lead on each side.

15 6. A taper hob formed by gashing and relieving a thread to form a series of finishing teeth which together generate the final finished shape of the work, said thread on each side being of changing pressure angle from one end to the other and being of different lead on opposite sides but of uniform lead on each along a line parallel to its root line.

20 25 7. A taper hob formed by gashing and relieving a multiple-thread worm to form a series of finishing teeth which together generate the final finished shape of the work, the threads of said worm being of increasing pressure angle on each side from the large to the small end of the hob and of different lead on their opposite sides.

30 35 8. A taper hob formed by gashing and relieving a multiple-thread taper worm to form a series of finishing teeth which together generate the final finished shape of the work, the threads of said worm being of increasing pressure angle on each side from the large to the small end of the hob and of different lead on opposite sides, but of uniform lead on each side.

30 40 9. A taper hob formed by gashing and relieving a multiple-thread worm to form a series of finishing teeth which together generate the final finished shape of the work, the threads of said worm being of increasing pressure angle from the large end to the small end of the worm and of uniform lead on one side measured along a line 45 parallel to the root line of the worm.

40 45 10. A hob formed by gashing a thread to form a series of finishing teeth which together generate the final finished shape of the work, said thread being of constant axial pitch on one side face 50 thereof and of a different constant axial pitch on the other side face thereof.

50 55 11. A taper hob formed by gashing a thread to form a series of finishing teeth which together generate the final finished shape of the work, said thread being of constant axial pitch on one side face thereof and of a different constant axial pitch on the other side face thereof.

55 60 12. A generating hob having a helical thread of a constant mean lead and consisting of a series of successive finishing teeth, said thread in one direction tapering uniformly both in width at the pitch line and in height, the sides of said thread having different leads.

65 70 13. A generating hob having a helical thread consisting of a series of successive finishing teeth thereon, said teeth having different constant axial pitches on the opposite profile generating faces thereof, and said teeth being of uniformly varying width at the pitch line.

70 75 14. A multiple-thread hob whose threads are each of different lead on opposite sides and are each gashed and relieved to form a series of finishing teeth which together generate the finished surface of the work.

15. A multiple thread hob whose threads are each of different but uniform lead on opposite sides and are each gashed and relieved to form a series of finishing teeth which together generate the finished surface of the work. 5
16. A multiple thread hob whose threads are each of straight profile in axial section but of different lead on opposite sides and are each gashed and relieved to form a series of finishing teeth 10 which together generate the finished surface of the work.
17. A multiple thread hob whose threads are each of straight profile in axial section and of different but uniform lead on opposite sides and are each gashed and relieved to form a series of finishing teeth which together generate the finished surface of the work. 15
18. A multiple thread hob whose threads are of different lead on opposite sides and are gashed 20 and relieved to provide a series of finishing teeth which increase in height from one end of the hob to the other and which together generate the finished surface of the work.
19. A multiple thread hob whose threads are of different but uniform lead on opposite sides and are gashed and relieved to provide a series of finishing teeth which increase in height from one end of the hob to the other and which together generate the finished surface of the work. 25
20. A multiple thread hob whose threads are of straight profile in axial section and of different lead on opposite sides and gashed and relieved to provide a series of finishing teeth which increase in height from one end of the hob to the other 30 and which together generate the finished surface of the work.
21. A multiple thread hob whose threads are of different but uniform lead on opposite sides and of straight profile in axial section and of continuously changing pressure angle from one end of the hob to the other and whose threads are each gashed and relieved to form a series of finishing teeth which together generate the finished surface of the work. 35
22. A multiple thread hob whose threads are each of different lead on opposite sides and of continuously changing pressure angle from one end of the hob to the other and whose threads are each gashed and relieved to form a series of finishing teeth which together generate the finished surface of the work. 40
23. A multiple thread hob whose threads are each of different but uniform lead on opposite sides and of continuously changing pressure angle from one end of the hob to the other and whose threads are each gashed and relieved to form a series of finishing teeth which together generate the finished surface of the work. 45
24. A multiple thread hob whose threads are each of straight profile in axial section but of different lead on opposite sides and of continuously changing pressure angle from one end of the hob to the other and whose threads are gashed and relieved to form a series of finishing teeth which together generate the finished surface of the work. 50
25. A multiple thread hob whose threads are each of different but uniform lead on opposite sides and of straight profile in axial section and of continuously changing pressure angle from one end of the hob to the other and whose threads are gashed and relieved to form a series of finishing teeth which together generate the finished surface of the work. 55

ERNEST C. HEAD.
